[57] CLAIM

The ornamental design for a portable radiotelephone, as shown and described.

DESCRIPTION

FIG. 1 is a left side, top and rear end perspective view of portable radiotelephone showing my new design in cradled relationship;

FIG. 2 is a left side, top and rear end perspective view thereof, shown with antenna in raised position;

FIG. 3 is a left side, top end and rear end perspective view of the handset and of its stand shown with the handset removed from, and spaced apart from, the stand;

FIG. 4 is a front elevational view thereof;

FIG. 5 is a rear end elevational view thereof;

FIGS. 6 and 7 are respectively right and left side elevational views thereof in cradled relationship; and

FIGS. 8 and 9 are respectively top and bottom plan view thereof in cradled relationship.

FIG. 1

FIG. 2

FIG. 3

FIG. 4

FIG. 5

FIG. 6

FIG. 9

FIG. 7

FIG. 8
